ERNEST ANSLEY WATSON, OF WEST ORCHARD, COVENTRY, ENGLAND, ASSIGNOR TO THE
M-L MAGNETO SYNDICATE LIMITED, OF WEST ORCHARD, COVENTRY, ENGLAND.

IGNITION APPARATUS FOR INTERNAL-COMBUSTION ENGINES.

1,302,107.

Specification of Letters Patent. Patented Apr. 29, 1919.

Application filed February 19, 1918. Serial No. 218,119.

To all whom it may concern:

Be it known that I, ERNEST ANSLEY WATSON, M. Sc., engineer, residing at Victoria Works, West Orchard, Coventry, in the county of Warwick, England, subject of the King of Great Britain and Ireland, have invented certain new and useful Improvements Relating to Ignition Apparatus for Internal-Combustion Engines, of which the following is a specification.

At the present time two main types of apparatus are employed for the production of high tension ignition sparks in internal combustion engines, namely, magnetos which generate their own current and induction coils which derive their current from a battery or dynamo. A characteristic of the magneto is that the energy content of the spark increases with the speed of operation of the machine, while the corresponding characteristic of the induction coil is that the energy content of the spark diminishes with the speed of operation. Generally with an induction coil there is a limit of speed beyond which no sparks can be obtained and at or just below that speed the sparking is irregular. The explanation of this difference is to be found in the fact that in the magneto the magnetic flux is produced in the core carrying the primary and secondary windings while the primary circuit is open and consequently the flux reaches its full value quickly and without any retarding effect due to an induced current in the primary. In the induction coil the primary must necessarily be closed before any magnetism can be set up therein and in consequence the rate of growth of the flux follows that of the current and depends upon the time constant of the circuit. The interval during which the circuit remains closed diminishes as the speed of rotation of the interrupter increases and as a result the magnetism available for use in producing the high tension spark diminishes also.

For high speed engines and particularly engines having a large number of cylinders there is a limit to the usefulness of an ordinary induction coil when as is necessarily the case in practice the size of the same is restricted.

The object of the present invention is to overcome the above described limitation to the induction coil type of ignition apparatus

(or what is commonly known as battery ignition apparatus which may derive its current from either a battery or a dynamo), and for this purpose the invention comprises the employment of means whereby magnetism is separately supplied to the core of the induction coil during the interval when the primary circuit is open. In particular the invention comprises the employment of a stationary primary and secondary winding herein termed the induction coil in conjunction with a magnetic system which consists in part of a rotary armature carrying an exciting winding, the armature being shaped to periodically open and close the magnetic circuit of the induction coil and supply the same with magnetism during the open circuit intervals of the primary.

Referring to the two accompanying sheets of explanatory drawings:

Figure 1 is a longitudinal section of an ignition apparatus constructed in accordance with this invention and adapted to provide twelve sparks per revolution.

Fig. 2 is an end view in which the four quadrants of the circular part shows different portions of the mechanism.

Fig. 3 is a cross section through the electro-magnetic system.

In applying the invention to battery ignition apparatus for a twelve cylinder engine, a circular rotary armature core *a* of disk form is provided on each side with a number of salient pole pieces *b*, each pole piece being bent at right angles so that it consists of a part which is radial to and is connected with the armature core, and a peripheral part which is parallel with the axis of the armature. The peripheral parts lie across the armature and inclose an annular winding *c* on the armature core. The poles of one disk lie alternately with the poles of the opposite disk, so that successive poles are of opposite polarity. In conjunction with the said peripheral portions of the poles are a pair of laminated limbs *d* extending from the opposite ends of a laminated core *e* carrying the primary winding *f* and secondary winding *g* of the induction coil. The disposition of the armature pole pieces and the magnetic circuit of the induction coil is such that during the rotation of the armature the pole pieces intermittently open and close the magnetic cir-

cuit through the induction coil and alternately magnetize the same in opposite directions.

Any suitable means such as a slip ring *h* 5 is provided to conduct current to the armature winding, and a mechanical interrupter of any convenient form (such as a cam *i* and contact lever *j*) is employed for opening and closing the circuit of the primary winding *f*. It will be understood that the armature winding and primary winding form 10 separate circuits to which current is conducted from a supply battery or direct current generator. The usual condenser *k* is arranged in conjunction with the interrupter. When the primary circuit is open 15 magnetism is supplied to the core of the induction coil by the armature. On closing the said circuit the magnetism is augmented by that induced by the current which flows 20 therein to the instant of breaking. At low speeds of rotation the magnetism due to the current in the primary may exceed that due to the armature. As the speed increases 25 the former diminishes, but the latter remains constant and is made sufficient to provide sparks of the required intensity at any speed. Thus at low speeds the working of 30 the apparatus is comparable to that of an ordinary induction coil, and at high speeds is comparable to that of an ordinary magneto.

In a convenient construction the mechanism is mounted in a hollow case *l* carrying 35 the armature and adapted for direct endwise attachment to the engine crank case in alinement with any convenient shaft such as the crank-shaft to which the armature spindle *m* is coupled. On the outer end of the 40 armature shaft is arranged the interrupter above mentioned and the distributor. In the drawings the latter is shown of the jump spark type consisting of a rotary radial arm *n* receiving high tension current from a 45 terminal *o* through a slip ring *p*, and terminals *q* which are connected to the engine plugs and convey current from the radial arm. The induction coil is carried in a 50 separate detachable housing *r* surmounting the case of the armature.

The invention is not limited to any particular constructional or mechanical details for carrying the same into effect as these may be varied without departing from the 55 invention.

Having thus described my invention what I claim as new and desire to secure by Letters Patent is:—

1. In ignition apparatus for internal combustion engines, consisting in part of an induction coil, a circuit breaker, and means independent of the circuit breaker, whereby magnetism is separately supplied to the induction coil during the open circuit period 65 of the coil, substantially as described.

2. In ignition apparatus for internal combustion engines, the combination comprising stationary primary and secondary windings, a core carrying the same, said windings and core forming an induction coil, a circuit breaker, a rotary magnetic system adapted to coöperate with the magnetic system of the coil and supply magnetism to the same during the open-circuit period of the primary winding of the induction coil, substantially 70 as described.

3. In ignition apparatus for internal combustion engines, the combination comprising primary and secondary windings and a core forming a stationary induction coil, core extensions, a circuit breaker, a rotary armature, salient poles on the armature co-acting with the core extensions and an exciting winding on the armature, the poles being arranged to intermittently supply magnetism 80 to the core during the open circuit period of the primary winding, substantially as described.

4. In ignition apparatus for internal combustion engines, the combination comprising 90 primary and secondary windings and a core forming a stationary induction coil, extensions on the ends of the core, a circuit breaker, a rotary spindle, a pair of iron disks formed with peripheral pole pieces on the 95 spindle, the pole pieces of one disk alternating with those of the other disk and the two sets of pole pieces being arranged to intermittently supply magnetism to the core during the open circuit period of the primary 100 winding, and an exciting winding between the disks, substantially as described.

5. In ignition apparatus for internal combustion engines, the combination comprising stationary primary and secondary windings 105 and core forming a stationary induction coil, a circuit breaker, core extensions, a rotary exciting armature provided with pole pieces co-acting with the core extensions and intermittently supplying magnetism to the core 110 during the open circuit period of the primary winding, a slip ring on the armature for conveying armature exciting current, a spindle carrying the armature, a high tension distributor arm and an interrupter cam 115 on said spindle, and an interrupter lever adjacent to the cam for controlling the current to the primary winding, substantially as described.

6. In ignition apparatus for internal combustion engines, the combination comprising primary and secondary windings, a core carrying said windings, parallel extensions on said core, a rotary exciting armature having its axis at right angles to the plane of the core and extensions, pole pieces on said armature for intermittently supplying magnetism to the core during the open circuit period of the primary winding, a spindle carrying the armature, a high tension dis- 120 125 130

tributer arm and an interrupter cam on the spindle, an interrupter lever adjacent to the cam for controlling the primary current, a slip ring on the armature carrying the armature exciting current, a cylindrical body carrying the armature and its associated parts, a distributor on one end of the body and a de-

tachable cover on one side of the body enclosing the primary and secondary winding, substantially as described. 10

In testimony whereof I have signed my name to this specification.

ERNEST ANSLEY WATSON.
